UNITED STATES PATENT OFFICE.

CHARLES H. MUCKENHIRN, OF DETROIT, MICHIGAN.

LIGHT.

Application filed August 4, 1921. Serial No. 489,706.

To all whom it may concern:

Be it known that I, CHARLES H. MUCKENHIRN, a citizen of the United States, residing at Detroit, in the county of Wayne and State of Michigan, have invented certain new and useful Improvements in Lights, of which the following is a specification, reference being had therein to the accompanying drawing.

10 This invention relates to an improved front for lights particularly automobile lights, tail lights, head lights, trouble lamps and the like.

15 The object of the invention is to provide an improved front or lens construction of an inexpensive nature that will be efficient in use and more durable than the usual glass lens.

20 The invention contemplates an improved front or lens composed of thin flexible film like material such as pyroxylin, celluloid, or like material, and of a cross sectional formation providing a succession of concentrically arranged projecting portions or bulges of 25 progressively varying diameter and with said projecting portions or bulges rounded and merging by easy or gradual curvatures into one another. the bulges or projecting portions in addition to functioning as light 30 diffusing or controlling portions, serving to reinforce and give sufficient stability to the structure, the resulting construction being less expensive to produce and more durable than a lens of glass, not subject to breakage 35 by dropping in handling or in shipment, and better able to withstand jars when in place in a lamp.

In the drawings:

40 Figure 1 is an elevation of a front or lens constructed in accordance with the present invention.

Figure 2 is a central section.

45 The invention with other objects and advantages thereof, and the particular construction comprising the same, will be understood from the following detail description, when considered in connection with the accompanying drawings forming part hereof and illustrating one embodiment of the invention.

While a specific embodiment of the invention is illustrated in the drawings, it will of course be understood that changes and variations in the particular construction shown, and the carrying out of the invention 55 in other forms, as will appeal to those skilled in the art, and falling within the scope of the appended claim, may be practiced without departing from the spirit of the invention.

60 In the drawing, the front or lens shown is particularly adapted for automobile rear or tail lights. A designates the front or lens formed from a thin flexible sheet of pyroxylin, celluloid or the like, and of a cross sectional shape providing a flat outer marginal part *a*, and, inwardly thereof, a 65 succession of concentrically arranged projecting portions or bulges *a'* of progressively varying diameters, said bulges or projecting portions *a'* in the particular construction shown, being rounded and merging by 70 easy curvatures into one another.

75 In the construction shown the flat outer marginal part *a*, which is adapted to be engaged by the usual lens holding means, (not shown), is shown provided with size indicating marks *a*².

80 The succession of bulges or projecting portions of progressively varying diameters act as light diffusing portions and additionally perform the important function of reinforcing and lending the required stiffness or stability to the structure. The particular rounded form of the bulges or projections merging into one another in easy 85 or gradual curvatures, as in the construction shown in the drawings, is especially advantageous in furnishing the required stiffness and at the same time permitting of lateral 90 springing or flexing without breakage in the case of extreme lateral pressure thereupon, and this special construction also possesses the important advantage that it 95 has no sharp corners or crevices for the lodgement of mud or dirt thereon and can be easily kept clean.

100 It will be noted that the particular construction of front or lens hereinbefore described, is of an inexpensive nature and is

not liable to breakage like the expensive glass lenses commonly employed.

What I claim is:—

As a new article of manufacture, a light-
5 housing closure composed of film-like flexi-
ble material having a succession of con-
centrically arranged projecting portions of
progressively varying diameters to reinforce
the closure, said projecting portions merg-

ing by easy curvatures into one another to 10
permit flexing of the closure under lateral
pressure without breakage.

In testimony whereof I hereunto affix my
signature in the presence of two witnesses.

CHARLES H. MUCKENHIRN.
